DES. 2278

P. L. Cambridge Jr. of Enfield, N. H.

Letters Patent No. 2278 Dated Mar 13, 1866

Design for a Bedstead.

The schedule referred to in these Letters Patent and making part of the same,

To all whom it may concern:

Be it known that I, P. L. Cambridge Jr. of Enfield in the County of Grafton and State of New Hampshire, have originated and produced a new design for a Bedstead of which the following is a full and clear description, reference being had to the accompanying drawings, making part of the specifications. This design is for the ornamentation of Bedsteads, or rather for the head and foot boards thereof, and more particularly to the face of the frame adjacent to the bed, and to the outer face of the latter. The design consists in the general configuration of the moldings surrounding the head and foot boards, and in the arrangement of the vertical panels, making the filling of the head frame and the horizontal panels forming the filling of the foot board.

The drawing represents an end elevation of the bedstead, showing the ornamental faces of the head and foot boards, in elevation.

a, denotes the centre moulding surrounding the head board, b, b, the mouldings connecting the same with the corner posts c, c. The head board d, contains vertical panels e, surrounded with moldings f, and arranged as seen in the drawing. The foot board, is surrounded by a central moulding g, and side moldings h, h, and contains horizontal panels i, surrounded by moldings k.

2

DES. 2278

I claim the ornamental design or configuration for the head and foot boards of a Bedstead, substantially as shown in the drawings.

In witness whereof I have hereunto set my hand this seventh day of February, A. D. 1866.

Witnesses,
E. J. W. T. Gould.
W. B. Crosby.
